[57] CLAIM

The ornamental design for an over-the-shoulder wallet, as shown and described.

DESCRIPTION

FIG. 1 is a front perspective view of an over-the-shoulder wallet showing my new design;

FIG. 2 is a rear perspective view thereof;

FIG. 3 is a left side view thereof;

FIG. 4 is a right side view thereof;

FIG. 5 is a bottom view thereof;

FIG. 6 is a top view thereof; and,

FIG. 7 is a front perspective view thereof, the broken lines showing a part of a human torso being for illustrative purposes only and forming no part of the claimed design.

FIG. 2

FIG. 1

FIG. 3

FIG. 4

FIG. 6
